UNITED STATES PATENT OFFICE

JAMES R. MOFFATT, OF CHICAGO, AND RALPH S. KELSO, OF ROCKFORD, ILLINOIS, AS
SIGNORS TO UNION SPECIAL MACHINE COMPANY, OF CHICAGO, ILLINOIS, A CORPO-
RATION OF ILLINOIS

SEWING MACHINE

Application filed June 4, 1926. Serial No. 113,714.

The invention relates to new and useful improvements in sewing machines, and more particularly to a sewing machine having a work supporting arm and a feeding mechanism arranged therein whereby tubular articles may be formed and stitched and fed off from the end of said arm.

An object of the invention is to provide a machine of the above type with an overhanging arm in the form of a hollow housing in which is located a rock shaft for operating the needle bar, a rock shaft for actuating the thread laying finger and the trimming devices, and a rock shaft which may be oscillated for lifting the presser bar.

A further object of the invention is to provide a machine of the above type wherein said overhanging arm is provided with a hollow head on the free end thereof, in which the greater portion of the actuating mechanisms for operating the needle bar, the thread finger and the trimming mechanism, are located.

A further object of the invention is to provide a machine of the above type having an overhanging arm mounted on a supporting bracket, wherein the arm is so attached to the bracket that the arm may be adjusted in a horizontal direction either lengthwise or transversely of the arm for positioning the needles relative to the throat plate on the work supporting arm.

A further object of the invention is to provide a machine of the above type wherein the work supporting arm extends across the post for supporting the same and is so connected to the post that the work supporting arm may be adjusted bodily, either lengthwise or transversely thereof for positioning the throat plate relative to the needles.

A further object of the invention is to provide a machine of the above type wherein the means for lifting the presser bar and the trimming devices is likewise located in said hollow head.

A further object of the invention is to provide a machine of the above type wherein the main shaft is located in a hollow housing disposed in front of the bracket on which

the overhanging arm is mounted, and on which hollow housing is mounted the post carrying the work supporting arm, and wherein an inclined housing joins the hollow housing carrying the main shaft with the bracket and the overhanging arm so that the devices for actuating the rock shafts in the overhanging arm may be arranged in said inclined housing.

A still further object of the invention is to provide a machine of the above type wherein the lower wall of the overhanging arm adjacent the bracket is inclined downwardly and leads in to the lower wall of the inclined housing, so that any oil dripping from the bearings in the overhanging arm, will drain from the overhanging arm into the inclined housing and thus to the hollow housing containing the main driving shaft.

A still further object of the invention is to provide a machine of the above type wherein the lower wall of the work supporting arm inclines toward the supporting post carrying the same and a channel is provided extending from said post along the bottom portion of said hollow member carrying the driving shaft so that oil dripping from the bearings for the main shaft and the looper shaft will drain back into the hollow housing for the main shaft, and to a point adjacent where the oil accumulates from the overhanging arm.

A still further object of the invention is to provide a machine of the above type wherein the tension devices for the various threads are mounted vertically one above the other and in substantially the same vertical plane as the stationary thread guides on the arm and the movable thread guides on the needle bar, so that the threads will pass in substantially the same plane from the supply to the needle bar.

A still further object of the invention is to provide a machine of the above type wherein the means for raising the presser foot also releases the tensions, and the tension releasing devices operate from beneath each pair of tension disks.

A still further object of the invention is

to provide a machine of the above type wherein the stationary thread eyes between the tension devices and the needle bar, are capable of vertical adjustment, angular adjustment and horizontal adjustment for varying the take-up control on the needle threads.

These and other objects will in part be obvious and will in part be hereinafter more fully disclosed.

In the drawings which show by way of illustration one embodiment of the invention—

Figure 1 is a front view of a machine embodying the improvements with the cover plate for the inclined housing removed;

Fig. 2 is a side view of the machine from the left as viewed in Fig. 1, with the cover plate for the head on the overhanging arm removed, the cover plate for the vertical post removed, and the cap for the end of the work supporting arm removed;

Fig. 3 is a sectional view on the line 3—3 of Fig. 2;

Fig. 4 is a sectional view on the line 4—4 of Fig. 2;

Fig. 5 is a detail in perspective, showing the operating arms for the movable trimmer blade and the thread laying finger;

Fig. 6 is a sectional view on the line 6—6 of Fig. 1;

Fig. 7 is a detail showing the bar for carrying the tension releasing devices;

Fig. 8 is a perspective view of the shiftable arm which engages and lifts the tension releasing bar;

Fig. 9 is a detail in section on the line 9—9 of Fig. 6;

Fig. 10 is a sectional view on the line 10—10 of Fig. 4;

Fig. 11 is a sectional view on the line 11—11 of Fig. 10, with the pitman rods omitted;

Fig. 12 is a plan view of the work supporting arm with the cover plate removed, and the looper omitted;

Fig. 13 is a view partly in longitudinal section through the work supporting arm and showing the means of supporting said arm whereby the same may be adjusted in a horizontal plane;

Fig. 14 is a detail showing the means for adjusting the stroke of the auxiliary feed dog;

Fig. 15 is a sectional view on the line 15—15 of Fig. 1, of the supporting means for the thread eyes, and

Fig. 16 is a sectional view on the line 16—16 of Fig. 10.

60 The invention is directed broadly to a sewing machine of the type wherein the material being stitched is formed into a tube about a work supporting arm and is fed off from the arm as it is stitched. A trimming mechanism is provided for trim-

ming the edges of the fabric which are to be stitched together. The stitching mechanism includes a plurality of needles and complementary stitch forming mechanism co-operating therewith beneath the fabric and the thread laying finger cooperating therewith above the fabric, so that the trimmed edges are joined by the united lines of stitching. The operating parts of the machine above the fabric are supported by an overhanging arm which is preferably of sleeve form, thus forming a hollow housing. Located in this hollow housing is a rock shaft for reciprocating the needle bar, a rock shaft for actuating the movable blade of the trimming mechanism and the thread finger, and a rock shaft which may be oscillated for lifting the presser foot and lifting the trimming mechanism from the material. The actuating members between these various rock shafts and the parts which are operated thereby, are, for the most part, housed in the hollow head at the end of the hollow overhanging arm. Thus it is that the parts are housed and protected from dust. This overhanging arm is mounted in a vertical bracket in turn mounted on a suitable supporting base. Projecting forwardly from the supporting bracket and attached thereto is an inclined housing, and at the lower outer end of this inclined housing is a sleeve or cylindrical housing for the main shaft. The main shaft is provided with a crank and an eccentric. The crank cooperates with a pitman which is connected to the shaft which operates the needle bar, and the eccentric is connected by a pitman or eccentric strap with the rock shaft which operates the thread finger and movable trimming blade. At the opposite end of this cylindrical housing for the main driving shaft from the inclined portion which is attached thereto, is a vertical post which carries the work supporting arm, and in this work supporting arm is located the feeding mechanism and the looper mechanism which cooperates with the needles. The work supporting arm extends entirely across the post, and is secured thereto by screws passing through openings in the arm which are of sufficient size to permit the free end of the work supporting arm to be shifted either laterally or longitudinally of the arm. This is for the purpose of bringing about a proper alignment of the needles with the throat plate on the work supporting arm. The overhanging arm extends across the top of the bracket on which it is mounted, and is connected thereto by bolts passing through openings which are of sufficient size so that the entire work supporting arm can be moved horizontally, either laterally or longitudinally for further aiding in positioning the needles relative to the throat plate on the work supporting arm. The

threads pass from the supply through a series of tensions which are mounted one above another in a vertical line on a vertically arranged support therefor. There is a plate which is movable vertically on this support, and this plate carries a finger underlying the tension disks. The upper edge of each finger is tapered so that when raised between the tension disks, it will separate the particular tension disks with which it cooperates. Means is provided for raising the plate when desired, and the raising means for the plate also raises the presser foot. The inner lower surface of the overhanging arm inclines toward the standard or supporting bracket therefor, so that the oil dropping from any of the bearings in the rock shafts will drain toward the bracket and drain into the inclined housing and run down said inclined housing into a well at the lower right-hand of the cylindrical housing containing the main shaft. There is also an oil passage so that the oil dropping from the bearings of the looper shaft will drain back into said well.

Referring more in detail to the drawings, the machine forming the present invention includes a supporting base 1 from which rises a bracket 2. Mounted on the upper end of the bracket 2 is an overhanging arm 3. This overhanging arm 3 is in the form of a hollow housing as clearly shown in the drawings. The overhanging arm extends entirely across the top of the bracket and is secured thereto by bolts 4, 4. These bolts pass through flanges formed at the top portion of the bracket 2, and are screwed into the under face of the overlying portion of the overhanging arm. The openings in the flanges are slightly larger than the clamping bolts as shown in Fig. 4 of the drawings. There are four of these bolts, two at the front side of the bracket and two at the rear side thereof. By loosening these bolts, the overhanging arm may be moved in a horizontal plane, either endwise or laterally, and this is for the purpose of positioning the needle head relative to the end of the work supporting arm, so that the needles will pass through the throat plate without striking the same. By this means, if there are any inaccuracies in the construction of the parts, the needle bar may be set so as to overcome these inaccuracies.

Projecting forwardly from the bracket 2 is an inclined housing 5. This inclined housing extends downwardly and is joined to a cylindrical housing 6 in which the main shaft 7 is located. This cylindrical housing 6 carries a vertical post 8 and mounted at the top of the vertical post 8 is a work supporting arm 9. The work supporting arm 9 extends all the way across the vertical post, and is secured thereto by bolts 10 (see Figures 2 and 12). The openings in the work

supporting arm through which these bolts pass, are slightly larger than the shanks of the bolts, and this permits the work supporting arm to be shifted either endwise or laterally at the free end thereof. This affords additional means for properly setting the free end of the work supporting arm relative to the needle bar, and the needles carried thereby. Through the combined adjustments of the work supporting arm and the overhanging arm, the needle bar can be set so that the needles will properly line up with the needle holes in the throat plate.

The present machine is particularly adapted for stitching tubular garments. The material to be stitched is placed beneath the projecting work supporting arm and is drawn up around the arm so that it may be fed along the arm and off from the end of the arm as it is stitched. The material is fed off from the end of the arm by a feeding mechanism which includes a main feed dog 11 and an auxiliary feed dog 12. The main feed dog 11 is carried by a feed bar 13, while the auxiliary feed dog is carried by an auxiliary feed bar 14. The auxiliary feed bar is mounted on the main feed bar and is raised and lowered therewith. This is accomplished by means of a lever 15 pivoted at 16 and connected to the main feed bar by a link 17. The lever 15 is oscillated by an eccentric strap 18 cooperating with an eccentric on the main shaft 7. The main shaft 7 projects into the lower portion of the vertical post 8, and this eccentric strap 18 is located in said post. The main feed bar is moved back and forth by means of a link 19 which is connected to a rock lever 20, and the rock lever 20 is connected to an eccentric strap 21 which cooperates with another eccentric on the main shaft 7. This eccentric strap 21 is likewise located in the vertical post. Through these two eccentric straps 18 and 21, the main feed dog is given all of its movements. The auxiliary feed dog is moved back and forth by means of a link 22 which is attached to a rocker 23 which in turn is connected to the main feed bar so that as the main feed bar moves back and forth, it will oscillate the rocker 23, and the rocker 23 will move the link 22 endwise. This link 22 is connected to a pivoted arm 24, and imparts oscillations thereto. The arm 24 is in turn connected by a link 25 to the auxiliary feed bar, and this moves the auxiliary feed bar back and forth. The stroke of the auxiliary feed bar can be varied by shifting the connection of the link 22 to the rocker 23. There is a slot 26 in the rocker which permits the connection of the link 22 to be shifted on the rocker. This is brought about by means of a hand lever 27 connected to and oscillating a disk 28. The disk 28 carries a pin 29 engaging the forked end of an arm 30. This arm 30 is

secured to a shaft 31, and the shaft 31 carries an arm 32 connected by a link 33 to the link 22. When the arm 32 is oscillated it will raise or lower the connection of the link 22 to the rocker 23. This feeding mechanism forms no part of the present invention, but is shown, described and claimed in our co-pending application Serial No. 83,914, filed January 26, 1926.

The machine contains three needles indicated at 34 in the drawings with which is associated the usual needle guard. Cooperating with these three needles beneath the work support is a single looper 35. The looper 35 is mounted on a looper shaft 36 which extends lengthwise of the work supporting arm 9 and is mounted in suitable bearings formed therein. This looper shaft is oscillated and is moved endwise by means of a link 37 which cooperates with a crank 38 on the main shaft 7. This link 37 is pivotally connected to an arm 39 mounted in an oscillating bracket 40, so that the upper end of the link moves in an elliptical path, and therefore, the looper shaft is not only oscillated but moved endwise.

The bottom surface 41 of the work supporting arm inclines downwardly toward the right as viewed in Fig. 13, and any oil dripping from the bearings for the looper, will drain to the right and run into the vertical post. The oil accumulating at the bottom of the post 8 will run through the passage 42 and along the channel 43 at the bottom of the cylindrical housing 6 and accumulate at the right-hand end thereof. The main shaft is driven by a belt wheel 44. On this main shaft is a looper thread take-up mechanism 45 and a looper thread pull-off mechanism 46, which is not described in detail, as it forms no part of the present invention. The looper thread passes through a channel 47, thence to the thread eyes associated with the pull-off, thence to the nipper 48, and thence to the thread eyes associated with the take-up for the looper thread. The thread after leaving the take-up passes through the channel 49 which leads to the channel 50 and thence along the channel 51 to the looper. The work supporting arm has a cover plate 52 which extends from the throat plate of the machine to the rear end of the work supporting arm as shown in Fig. 2 of the drawings. Said cover plate is secured by a suitable screw to the work supporting arm. The purpose of making the cover plate extend the full length of the work supporting arm is to expose the bolts 10 when the cover plate is removed. This provides means whereby the bolts 10 are readily made accessible for adjusting the position of the work supporting arm.

The needles 34 are mounted on a needle bar 53. This needle bar is mounted to re-

ciprocate in the needle head at the free end of the overhanging arm 3. The overhanging arm 3 is hollow, as above noted, and terminates at its free end in an enlarged hollow head which is referred to above as 70 the needle head. Said hollow head is provided with a relatively long bearing 54 which receives the upper end of the needle bar 53. There is a bearing 55 at the lower portion of the needle head for the needle bar. The needle bar in its reciprocations does not pass above the top bearing 54 so that the needle bar at the upper portion thereof is continually housed within the hollow head. Extending lengthwise of the 75 overhanging arm 3 is a rock shaft 56. Said rock shaft is mounted in the bearings 57, 58 and 59, all of which are formed as a part of the overhanging arm. This permits the overhanging arm to be bodily shifted after 80 the manner above described without creating any bind on the rock shaft 56. This rock shaft 56 is provided with an arm 60, which carries a ball stud at its lower end 61. A pitman 62 is connected to the ball 85 stud at its upper end and is connected to a crank 63 at its lower end, which crank is formed as a part of the main shaft 7. As the main shaft rotates, the crank through this pitman 62 will oscillate the rock shaft 90 56. On the outer end of the rock shaft 56 there is an arm 64. This arm 64 (see Figures 2 and 3) is connected by means of a link 65 to a lug formed as a part of a sleeve 66 which in turn is clamped to the needle bar. As the rock shaft oscillates, it will 95 reciprocate the arm 64, and this will reciprocate the needle bar.

The material is held on the work support by a presser foot 67. The presser foot 67 is carried by a presser bar 68. The presser bar 68 is mounted in the bearings 69 and 70 at the upper and lower ends, respectively, of the needle head. Mounted on the presser bar is a collar which is provided 105 with a forked arm 71, and this forked arm 71 straddles a guide bar 72 which is mounted in the bearing 70. The guide bar is stationary and the forked arm 71 moves 110 up and down thereon. The purpose of the 115 guide bar is to cooperate with the presser bar in preventing the presser foot from turning laterally. This is essential in view of the fact that the trimming mechanism which will be described later, includes a 120 stationary trimming blade mounted on the presser foot. The presser bar is raised by means of a rock shaft 73 which is mounted in suitable bearings in the overhanging arm and is provided with a collar 74 at its inner 125 end. Said collar is in turn provided with an arm 75 which projects through a slot 76 in the cover plate 77 secured to the rear side of the overhanging arm. A spring 78 encircles the rock shaft 73 and engages 130

the arm 75 and normally holds the arm raised to the upper end of the slot 76, said upper end of the slot serving as a stop to limit the movement of the arm 75. The presser bar 68 is moved downwardly until the presser foot engages the material by a leaf spring 79. This leaf spring 79 bears on the upper face of a lug formed as a part of a sleeve 80 which is rigidly secured to the presser bar 68. The leaf spring at its rear end bears on a fulcrum support 81 and is put under tension by an adjustable screw 82. On the end of the rock shaft 73 there is an arm 83 which underlies the lug on the sleeve 80. When the operator depresses the arm 75, it will oscillate the shaft 73 and lift the arm 83 into engagement with this lug which is attached to the presser bar, and thus the presser foot can be lifted from the material.

20 The trimming mechanism which trims the fabric and thus prepares the edges of the fabric for the stitching mechanism consists of a stationary trimming blade 84 which is mounted on a presser foot, and a movable trimming blade 85 which is carried by an arm 86 fixed to the lower end of a yoke 87. The yoke 87 is mounted on the presser bar 68 so that it may oscillate freely 25 on the presser bar. The yoke is moved downwardly on the presser bar so as to bring the movable trimming blade into shearing relation with the stationary trimming blade by a spring 88 which lies between the upper end of the yoke and a collar 89 secured to the presser bar. This provides a means whereby the movable blade will be yieldingly forced against the stationary blade, and at the same time, both 30 blades may be raised and lowered with the presser foot.

40 Cooperating with the needles 34 is a thread hook or finger 90. This thread hook or finger 90 is carried by an arm 91 which is mounted on a yoke 92. The yoke 92 is freely mounted on the presser bar. One arm of the yoke 92 is directly above the bearing 70, and the other arm of the yoke is directly beneath the bearing 70. This 45 forms a construction wherein the yoke may readily oscillate on the presser bar, but the yoke is not raised and lowered with the presser bar. In other words, the presser bar slides freely in the yoke 92.

50 Mounted in the overhanging arm is a rock shaft 93. This rock shaft 93 is provided with an arm 94 in its inner end. At the lower end of the arm 94 is a ball stud 95. A pitman or eccentric strap 96 55 engages at its upper end the ball stud 95, and at its lower end cooperates with an eccentric 97 on the main shaft 7. As the main shaft rotates, it will move the pitman or eccentric strap 96 endwise, and this will 60 oscillate the shaft 93. Said shaft 93 has a

rigid head 98 secured at the outer end thereof, just beyond the bearing 57. This head 98 carries an arm 99 which projects through a slot in the cover plate 100. At the outer end of the arm 99, there is a link 101. This link 101 is connected at its other end to a ball stud 102 carried by an arm 103 formed integral with the yoke 87. Said head 98 is provided with a depending arm 104, and this depending arm 104 is connected to a link 105, and the link 105 is in turn connected to a ball stud 106 carried by the yoke 92, which supports and operates the thread finger or hook 90. The depending arm 104 passes through a slot in the lower 70 part of the overhanging arm. It will be noted that all of the mechanism between the rock shaft 56 and the needle bar is housed within the head at the end of the overhanging arm. It will also be noted 75 that quite a portion of the actuating mechanism for the hook and also for the movable trimming blade is likewise housed within this hollow head. Thus it is that the moving parts are protected from dust and 80 lint. Furthermore, by said arrangement of parts, the region where the stitches are formed, and the trimming takes place, is 85 comparatively free from obstruction and open to view by the operator of the machine. The means carried at the needle head for operating the thread laying and the trimming devices form no part of the present invention, but are shown, described and claimed in our co-pending application, 90 Serial No. 242,118, filed December 23, 1927.

The bottom portion or what might be termed the floor 107 of the overhanging arm inclines from the bearing 57 rearwardly toward the inclined housing 5. The inclined 95 housing 5 also inclines downwardly so that any oil dripping from the bearings, will 100 drain into the housing 5 and run down the housing 5 into the well at the lower end of the housing. Thus it is that the oil dripping 105 from the bearings, both in the overhanging arm and in the work supporting arm, and the bearings in the cylindrical housing for the main shaft, will accumulate 110 at the lower right-hand end of this cylindrical housing for the main driving shaft, and may be drawn off through the port 115 108 at suitable intervals.

Both the eccentric strap and the pitman are of peculiar construction. This is clearly shown in Fig. 16, which is a cross sectional view of all of these parts. The parts are similar in construction. Each member is formed so that it is solid, and is provided with longitudinal ribs. The longitudinal 120 ribs are arranged ninety degrees apart, and are of greater radial extent in the central portion of the strap or pitman. This makes a very durable construction of operating pitman which is very light and yet very strong. 125

The housing 5 and the bracket 2 are preferably cast integral. The covering plate 77 for the overhanging arm aids in the assembling of the pitmans or eccentric strap. The cover plate 109 is for the purpose of covering an opening in the end of the overhanging arm which facilitates the placing of the rock shafts in their bearings, and a cover plate 110 at the upper face of the overhanging arm aids in giving access to the parts which connect the pitman and the eccentric strap to the rock shafts. A cover plate 111 covers an opening in the inclined housing 5 which gives access to the crank and the eccentric on the main shaft and also aids in the assembling of the eccentric strap and the pitman.

The threads for the machine are led through thread guides formed in a bracket 112. As illustrated in the drawings, there are five threads, one for each of the needles, one for the looper, and one for the thread laying finger or hook. The bracket 112, therefore, has five thread eyes, and these thread eyes are located one above the other in a vertical line. Mounted on the front of the overhanging arm 3 is a supporting bracket 113. Fixed to this supporting bracket 113 are five tension posts, each of which is supplied with a pair of tension disks and spring tension means which may be of the usual construction. The bracket 113 is provided with thread eyes indicated at 114, arranged one above the other, through which the threads pass after leaving the thread eyes in the bracket 112. There is one thread eye 114 for each pair of tension disks, and these thread eyes are located slightly below the respective tension disks with which they are associated. Directly opposite the thread eyes 114 is a series of thread eyes 115, one for each thread. It will be noted that the thread passes through the thread eye 114, then upwardly and between the tension disks, and thence downwardly and through the thread eye 115. By this arrangement of thread eyes and tension disks, gravity will aid in holding the thread between the tension disks, even after the tension disks are separated to release the tension on the thread. The three needle threads after leaving the thread eyes 115, pass through thread eyes 116 in an arm 117, and thence through thread eyes 118 in an arm 119 which is secured to and reciprocates with the needle bar. The arm 119 is adjustably secured to the sleeve 66, which is fixed to the needle bar. The arm 117 is adjustably secured in a sleeve 120 which in turn is carried by an arm 121 mounted for longitudinal adjustment in a supporting bracket 122. This provides means whereby the arm 117 can be adjusted vertically, shifted horizontally, and the upper end thereof in which the thread eyes are formed,

can be adjusted angularly in the supporting sleeve 120 therefor.

It is noted that the tension disks, the bracket 112, the thread eyes 116, and the thread eyes 118, all lie in substantially the same vertical plane, so that the threads as they run from the supply to the needle bar are substantially free from being bent sharply about corners. The thread eyes 116 cooperate with the thread eyes 118 in the effective taking up of the threads in the setting of the stitch, and by adjusting the position of the thread eyes 116, the amount of thread taken up may be varied.

Associated with the bracket 113 is a plate 123. This plate is provided with suitable openings 124, through which tension posts extend. The plate is also provided with a series of arms 125 which are normally located directly beneath the respective tension disks. The upper edge of each arm 125 is beveled so that when the arm is moved upwardly by the lifting of the plate 123, said arm will pass between the tension disks and separate the tension disks so as to release the threads from tension. Inasmuch as the arms 125 are beneath the tension disks, gravity will aid in the moving of the arms away from the tension disks. This plate 123 is raised by means of an arm 126 which projects through a slot 127 into the interior of the overhanging arm. The arm 75 mounted on the rock shaft 73 has a portion 128 which projects beyond the rock shaft 73 (see Fig. 6). An extension arm 129 is freely journaled on the shaft 73 and is provided with a slot 130, through which a set screw passes for securing said extension arm in adjusted positions on the forwardly projecting portion 128 of the arm 75. This arm 129 has a laterally projecting part 131 which is adapted to engage the arm 126 (see Figures 6 and 9). When the presser foot is raised through the depressing of the arm 75, the part 131 through its engagement with the arm 126 will lift the plate 123 and this will separate all of the tension disks and release the tension on all of the threads. The tension disk and the releasing means therefor form no part of the present invention, but are shown, described and claimed in our co-pending application, Serial No. 298,514, filed Aug. 9, 1928.

The covering thread for the finger or hook 84 passes through a second tension disk 120 from the bottom, and thence through a thread eye 132 in the lower end of the arm 117. After leaving this thread eye 132, it passes through one of the thread eyes 133 in an arm 134 clamped to the arm 104, which actuates this thread finger or thread hook 84. After leaving this thread eye 133, it passes through a stationary thread eye 135 carried by a rigid arm 136.

The function and operation of the various

parts of the machine have been described in connection with the detail description of each part, and further description of the operation of the machine is not thought necessary. It will be understood, of course, that changes may be made in the details of construction without departing from the spirit of the invention as set forth in the appended claims.

Having thus described the invention, what we claim as new and desire to secure by Letters Patent, is—

1. A sewing machine including a support, an overhanging arm extending across the upper end of said support, means for securing said overhanging arm to said support so that said arm can be adjusted horizontally, a housing in front of said support and connected thereto, a vertical member at the end of said housing, a work supporting arm extending across the end of said vertical member, and means for connecting said work supporting arm to said member so that said work supporting arm can be adjusted horizontally.

2. A sewing machine including a support, an overhanging arm extending across the upper end of said support, means for connecting said overhanging arm to said support so that said overhanging arm can be adjusted horizontally, a needle bar at the outer end of said overhanging arm, actuating devices located in said overhanging arm for reciprocating the needle bar, a housing in front of and connected to said support, a main shaft in said housing, and means operated by said main shaft for operating said actuating devices in the overhanging arm, the connection between the operating means for the actuating devices being such as to permit the horizontal adjustments of the overhanging arm.

3. A sewing machine including in combination a support, an overhanging arm extending across the upper end of said support, means for securing said overhanging arm to said support so that said overhanging arm can be adjusted horizontally on said support, a needle bar mounted in the outer end of said overhanging arm, a rock shaft in said overhanging arm connected to said needle bar for reciprocating the same, a housing in front of and connected to said support, a main shaft in said housing, a pitman connected to said rock shaft and operated by said main shaft, said connection between the pitman and the rock shaft being such as to permit the horizontal adjustments of said overhanging arm.

4. A sewing machine including in combination, an overhanging arm, a support on which said arm is mounted, an inclined housing attached to the support and projecting forwardly therefrom, a horizontal housing at the lower end of said inclined housing, the

inner face of said overhanging arm adjacent the support being inclined so that any oil accumulating therein will drain into said inclined housing and pass down said inclined housing to an accumulating well in the horizontal housing, a vertical member attached to said horizontal housing, a work supporting arm carried by said vertical member, the inner under face of said work supporting arm being inclined toward the vertical post so that oil dropping therein will drain to the bottom of said vertical post, said housing having a channel leading from the bottom of said vertical post to said well in which the oil accumulates, whereby the oil dropping from the actuated parts in the machine will accumulate in a central well from which it may be drawn at intervals.

5. A sewing machine including a supporting frame including a standard, an overhanging arm extending across the upper end of said standard, a needle bar mounted for reciprocation in the outer end of said arm, an actuating shaft mounted in said arm, devices actuated thereby for reciprocating said needle bar, said supporting frame including a vertically disposed post, a work supporting arm carried at one end thereof, a feed dog located at the outer end of said arm for feeding the material lengthwise of the arm, a looper mounted at the outer end of said arm and cooperating with the needle carried by the needle bar, means for securing said overhanging arm to said standard whereby the same may be shifted horizontally, and means for securing said work supporting arm to said post whereby the same may be shifted horizontally whereby the outer ends of said overhanging arm and said work support may be shifted relative to each other.

In testimony whereof, we affix our signatures.

JAMES R. MOFFATT.
RALPH S. KELSO.
